(57) **CLAIM**

The ornamental design for the combined sandal upper and midsole, as shown and described.

DESCRIPTION

FIG. 1 is a top perspective view of my ornamental design for a combined sandal upper and midsole;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines in the drawings depict parts of the combined sandal upper and midsole that form no part of the claimed design.
